GAS VALVE

George F. Turner and Vincent C. Peterson, Chicago, Ill., assignors to Harper-Wyman Company, Chicago, Ill., a corporation of Illinois

Application February 12, 1941, Serial No. 378,511

15 Claims. (Cl. 74—504)

The present invention pertains to gas valves and more particularly to the provision of gas valves with new and improved valve position indicating and determining means. This means is particularly adapted for use in conjunction with a double gas valve, that is, a gas valve having two outlet passageways through which gas may be selectively supplied to the simmer section or to both the simmer and main burner sections of a double gas burner. More specifically, the present invention is directed to the provision of a position indicating and determining mechanism for a gas valve operable from an off to full on positions through a plurality of intermediate positions.

The primary object of the present invention is to provide a valve position indicating and determining means which is capable of producing an audible click for one intermediate position and resisting turning movement of the valve for a plurality of other intermediate positions.

A more specific object of the present invention is to provide a valve mechanism having stops for determining the off and full on positions and having associated therewith means providing an audible click when the valve is operated to an intermediate simmer position and resistance to turning of the valve for two other intermediate positions of the valve.

A further and more specific object of the present invention is to provide a valve of the type described with position determining and indicating means capable of producing an audible sound when the valve is rotated in either direction to a simmer position.

Other objects and advantages of the present invention will become apparent from the ensuing description, in the course of which reference is had to the accompanying drawings, in which:

Fig. 1 is a top plan view, partly broken away, of a gas valve embodying the present invention, the valve being illustrated in its off position;

Fig. 2 is a front elevation, on an enlarged scale, of a closure member forming part of the position indicating and determining means illustrated in Fig. 1;

Figs. 3 to 8 are cross-sectional views on an enlarged scale taken along the line 3—3 of Fig. 1, illustrating various positions of the valve plug. Of these figures, 4 to 8, inclusive, are fragmentary;

Figs. 3A to 8A are cross-sectional views taken along the line A—A of Fig. 1, illustrating the corresponding positions of the position indicating and determining mechanism;

Fig. 9 is a view similar to Fig. 2 of a modified form of closure member; and

Fig. 10 is a front elevation of a modified form of detent plate to be used in conjunction with the closure member illustrated in Fig. 9.

Referring now more particularly to Figs. 1 and 3A, the double gas valve with which the position indicating and determining means of the present invention are utilized is indicated by reference character 10. It comprises a valve body 12 within which is mounted a rotatable control member illustrated as a tapered plug 14. The plug is provided with an axial passageway 16 providing communication between the interior 13 of the valve plug and a chamber 17 (see Fig. 1) within which the plug is mounted. The plug is provided also with a pair of main radially disposed passageways 18 and 20 located approximately 90° from each other and a small auxiliary passageway 22 located between the main radial passageways. The end of passageway 22 at the outer surface of the valve plug is enlarged, as indicated by reference character 23, for a purpose to be described hereinafter. The valve plug is rotatable by a handle 24 secured to a valve stem 26 formed integrally with the plug and having a substantially D-shaped cross section.

The position indicating and determining mechanism of the present invention comprises a detent plate or washer 28 surrounding and movable by the valve stem and a closure plate 30. The latter is provided with a pair of inwardly extending projections 32 and 33 and surrounds the valve stem but is fixedly secured to the valve body. Plate 28 is urged toward plate 30 by a spring 34 surrounding the valve stem and serving also to urge the valve plug toward its seat. The specific construction and operation of the position indicating and determining mechanism will be described in greater detail after brief consideration is had of the valve which, while forming no part of the present invention, should be understood in order that a better understanding may be had of the present invention. The valve construction itself forms the subject matter of the co-pending application of Philip S. Harper, Gas valves, filed contemporaneously herewith.

The valve body is provided with a gas inlet passageway 36 formed as by a drilling operation in a boss 38 that is exteriorly threaded for attachment to the usual gas supply manifold, not shown. The valve body is also provided with a pair of axially extending, spaced apart, exteriorly threaded bosses 40 and 42 that are drilled to form gas outlet passageways 44 and 46 through

which gas is supplied to the simmer and main burner sections, respectively, of a double gas burner, not shown. Passageway 44 communicates directly with chamber 17 and therethrough with axial passageway 16 of the valve plug, as shown in the cutaway portion of Fig. 1, and passageway 46 communicates with the plug surface through a passageway 48 drilled into a boss 50 also formed integrally with the valve body but closed as by a plug 52. Adjustably mounted hoods 54 provided with orifices and cooperating with fixed needle valves, not shown but of conventional construction, are secured to the outer ends of bosses 40 and 42 to provide nozzles through which gas is supplied to the burner sections at suitable velocities when the valve is in its full on position.

The valve body is provided also with a further boss 56 within which is mounted a valve member 58 adjustable to vary the amount of gas supplied to the simmer section when the valve plug is rotated into its low simmer position, as will be described in greater detail hereinafter. Any suitable valve mechanism may be employed to provide the adjustment, although the one illustrated is of an improved construction forming the subject matter of the co-pending application of Turner et al., filed contemporaneously herewith. The valve member 58 is adjustably mounted in an insert 59 to vary the flow of gas through a small passageway 60 formed at the reduced end portion of the insert and communicating with the valve plug surface through a passageway 62. The interior of the insert communicates with the inlet passageway 36 through a passageway 64 formed in the insert, an annular chamber 66 formed by the reduced end portion of the insert and the interior of boss 54, and a passageway 68 leading to the inlet passageway. Leakage of gas and undesired movement of the adjustable valve 58 are prevented by a cap 70 and a sealing gasket 72.

The construction of the position indicating and determining mechanism may best be ascertained from Figs. 2 and 3A to which reference will now be had. The closure plate 30, illustrated in Fig. 2, has a substantially diamond-shaped contour and is secured to the valve body by a pair of screws 74 and 76 in such manner that the projection 32 is located near the top of the valve and approximately 20° to the left of the vertical center line of the valve, the projection 33 being diametrically opposite projection 32. The plate 30 is also provided with a central circular aperture 78 of a diameter slightly larger than that of the valve stem. The front end of the valve body proper is cut away to provide a space 80 for the reception of the projections 32, 33, the plate 30, and spring 34. The space or recess is also cut to provide a shoulder 82 cooperable with the detent plate 28 to determine the off position of the valve, and a second shoulder 84 likewise cooperable with the plate to determine the full on position of the valve.

The detent plate is provided with a relatively short arcuate projection 86 including an angle of about 42° for engaging the shoulders 82 and 84 at the limiting off and full on positions of the valve. The detent plate 28 is also provided with a substantially centrally located aperture 88 of a diameter slightly greater than that of the valve stem and defining an angular opening sufficient to permit relative movement between the plate and valve stem, the extent of relative

movement being approximately 36°. The portion of the detent cooperating with the flat side of the valve stem comprises a rounded apex 90 and flat portions 92 and 94 defining surfaces at angles of about 18° to a line tangential to the apex 90. The detent plate 28 also comprises a pair of opposed arcuate projections 100 and 102 equidistant radially from the axis of the valve and valve stem and adapted to clear the shoulders 82 and 84. The previously referred to projection 86 is located substantially centrally of arcuate projection 102, thus constituting a reduced extension of the latter. Projection 100 defines a pair of shoulders 104 and 106 and the arcuate portion 100 similarly defines shoulders 108 and 110 for cooperation with projections 32 and 33 to indicate and determine the heretofore referred to intermediate valve positions. Shoulders 104 and 110 and shoulders 106 and 108 are diametrically opposite each other, respectively. Shoulders 104 and 108 on the one hand, and shoulders 106 and 110 on the other may be considered as formed by arcuate recesses in the detent plate.

The operation of the valve and the position and determining mechanism may best be understood by considering the various positions of the valve. In introduction it may be stated that the valve illustrated may supply a double burner with sufficient gas to provide from 9,000 to 12,000 B. t. u. when the valve is in its full on position, the gas being supplied to both the main and simmer burner sections. It may also supply gas sufficient to furnish about 1200 B. t. u. in its simmer position, the gas being supplied only to the simmer section. In the low simmer position the amount of gas supplied to the simmer section may be sufficient to provide heat at a rate of about 250 B. t. u. These rates, it should be understood, are intended merely to be illustrative.

From the foregoing it may be noted that only a very limited amount of gas is supplied to the burner in the low simmer position, and when supplied is not enough always to insure proper lighting of the burner by the usual automatic lighting means. It is, therefore, preferable that the valve be operated to its simmer position when initially lighting the burner. In order to enable the users of the valve to do this, the position indicating and determining means is so constructed and arranged as to provide an audible sound or click when the valve is operated from its off to its simmer position. The construction is such also that an audible click is given when the valve is operated to a simmer position after having been turned to its full on position.

Referring now more particularly to Figs. 3 to 8 and 3A to 8A, both inclusive, it may be noted that they illustrate various positions of the valve and corresponding positions of the position indicating and determining mechanism.

The off position of the valve and corresponding position of the position indicating and determining mechanism are illustrated in Figs. 3 and 3A, respectively. Upon reference to Fig. 3, it may be noted that the main and branch inlet passageways are sealed from both the simmer and main burner section outlet passages. At this time the outermost projection 86 of the detent plate 28 abuts against the shoulder 82, and projections 100 and 102 are over projections 32 and 33 of closure plate 30, against which they are urged by the spring 34. The position of the valve operating handle 24 obtaining when the valve is in its off position is indicated by the

arrow A in Fig. 3. In passing, it might be well to note that the position of the handle is similarly indicated by the arrow A in Figs. 4 to 8.

The first operative position of the valve is, as indicated above, its simmer position, at which time sufficient gas is supplied to the simmer section of the burner to insure ignition thereof by automatic lighting means. The position of the burner is illustrated in Figs. 4 and 4A. From Fig. 4 it may be noted that the main gas inlet passage 36 communicates with the axial passage 18 of the valve plug through radial passageway 18 and thereby with the simmer section gas outlet passageway 44. No gas, however, is supplied to the main burner section, the passage of gas there-to being prevented by the valve plug. As the valve plug is rotated in a counterclockwise direction from the off position indicated in Fig. 3 to the simmer position indicated in Fig. 4, initial movement of the operating handle 24 results in rotating of the valve plug but not of the detent plate 28 by reason of the lost motion connection between the valve stem and detent plate. However, upon continued rotation of the valve, the flat surface of the valve stem engages the portion 92 of the detent plate to effect rotation of the latter. As the detent plate is rotated in a counterclockwise direction, the shoulders 106 and 108 of arcuate projections 100 and 102, respectively, reach the edge of the projections 32 and 33, and the spring 34 effects rapid movement of the detent plate toward and against the plate 30, the lost motion connection between the detent plate and valve stem permitting rapid movement and the jumping of the plate a slight distance beyond the projections as illustrated in Fig. 4A.

From the simmer position the valve may be operated further in a counterclockwise direction or it may be moved in a clockwise direction to the low simmer position indicated in Figs. 8 and 8A. However, it will be assumed that the valve is operated further in a counterclockwise direction. Continued operation of the valve in this direction results in the continued supply of gas to the simmer section. When the valve is rotated to the position indicated in Fig. 5, that is, somewhat less than 180° from its off position, the lost motion between the valve stem and detent plate resulting from the jumping of the latter is taken up and the detent plate shoulders 110 and 104 are moved against projections 32 and 33, respectively. The projections serve moderately to restrict movement of the valve operating handle, thereby indicating to the operator that further movement will result in the supply of gas to both the main and simmer burner sections at a low rate.

The valve may be operated further in a counterclockwise direction until the arcuate projections 102 and 100 overlie projections 32 and 33, respectively, thereby to supply gas to the valves at a regulatable rate until the projection 86 strikes shoulder 84 to indicate the full on position. This position of the valve is indicated in Fig. 6. Gas is supplied to both the simmer and main burner section outlet passageways 44 and 46 through the main inlet passageway 36, the gas flowing to the simmer burner outlet passageway through the axial passageway in the plug and to the main burner section outlet passageway through the radial passageway 18. The auxiliary radial passageway 22-23 in the valve plug serves to prevent sealing of the main gas inlet passageway 36 by the valve surface between radial passageways 18 and 20 as the valve is operated from its sim-

mer to its full on position. In other words, it provides an even final or low turn down range when gas is being supplied to both burner sections.

5 When it is desired to reduce the quantity of gas supplied to the burner, say to a point where gas is supplied to the simmer section only, the valve is rotated in a clockwise direction until an audible click is heard. The click results in the same 10 manner as heretofore described, although at this time the valve is at a slightly different angle than in the simmer position illustrated in Figs. 4 and 4A. However, in this second simmer position, gas is again supplied solely to the simmer 15 section of the burner, as indicated in Fig. 7. The click results from the movement of arcuate projections 102 and 100 off the projections 32 and 33, respectively, by the action of the spring 34, the detent plate then occupying the position illustrated in Fig. 7A.

To operate the valve into its low simmer position from either of the simmer positions, that is, the simmer positions of Figs. 4, 4A, and 7 and 7A, the valve is rotated in a clockwise direction 25 until movement of the valve is restricted by detent plate shoulders 106 and 108 striking projections 32 and 33, respectively, as indicated in Fig. 8A. At this time gas is supplied to the simmer section through the branch passageway 30 68 and at a rate determined by the adjustment of valve 58.

When the valve is returned to its off position, the valve and position indicating and determining mechanism occupy the positions illustrated in 35 Figs. 3 and 3A, and which have already been described.

From the foregoing description of the operation of the valve and position indicating and determining mechanism, it is to be noted that an audible click is given at one of the several intermediate positions and that movement of the valve is restricted in other intermediate positions. While in the instant embodiment restriction of movement occurs at two different angular positions to indicate the simmer position of the valve, it should be understood that the second simmer position might very well be some other operative position of the valve which could be indicated by the restriction of movement. Consequently, while the present invention has been described in conjunction with a specific form of valve, it should be understood that it is applicable to other forms of valves as well. Furthermore, the construction of the two plates may be reversed, i. e., the shoulder defining closure plate may be fixedly secured relative to the valve body and the movable detent disc may be provided with the projections.

A construction of this type is illustrated in Figs. 60 9 and 10 to which reference will now be had. The fixedly secured plate 112 illustrated in Fig. 9 is provided with a central aperture 114 through which the valve stem extends. It is also provided with diametrically opposite arcuate apertures or recesses 116 and 118 providing four spaced apart shoulders 120, 122, 124 and 126. The apertures are so located that the shoulders are positioned in the same places as the shoulders of the detent plate of the previously described embodiment when the plate is in its off position.

The detent plate 128 illustrated in Fig. 10 is provided with a central aperture 130 corresponding in construction with the aperture of detent plate 28. The plate is constructed with opposed arcuate portions 132 and 134 provided

with projections 136 and 138, respectively, of relatively narrow arcuate width and located to cooperate with the shoulders of plate 112. Projection 134 has an arcuate portion 140 corresponding to portion 86 of the previously described embodiment for determining the limit positions of the valve.

The detent plate 128, in the off position of the valve, occupies a position corresponding to the detent plate 28 shown in Fig. 3A, in which position the projections 136 and 138 are centrally located relative to portions of the plate 112 between the apertures. The other operative positions of the valve and of the closure and detent plates correspond to those of the previously described embodiment so that further description thereof is not deemed to be necessary.

What we claim as new and desire to secure by United States Letters Patent is:

1. A position indicating and determining mechanism for a valve comprising a body and operable by a rotatable stem extending outside the body, including in combination, a first plate fixedly secured relative to said body and apertured for the passage of the stem therethrough, a second plate located adjacent said plate and rotatable by said stem, and spring means for urging said second plate toward said first plate, one of said plates being provided with substantially diametrically opposite projections of relatively narrow arcuate extent and the other with substantially diametrically opposite portions each defining a pair of shoulders cooperable with said projections to restrict rotation of the stem, said shoulders being spaced apart a distance such that substantial unrestricted rotation of the stem may be effected in either direction when the projections are between a pair of shoulders defined by one portion or between adjacent shoulders defined by both portions.

2. A position indicating and determining mechanism for a valve comprising a body and operable by a rotatable stem extending outside the body, including in combination, a first plate fixedly secured relative to said body and apertured for the passage of the stem therethrough, a second plate located adjacent said plate rotatable by and having a loose connection relative to said stem, and spring means for urging said second plate toward said first plate, one of said plates being provided with a projection of relatively narrow arcuate extent facing toward the other plate, and said other plate with a pair of substantially diametrically opposite arcuate portions of greater arcuate extent than said projection and adapted to displace said first plate against said spring when positioned over said projection, each of said portions defining a pair of spaced apart shoulders cooperable with said projection moderately to restrict rotation of the stem, said shoulders being spaced apart a distance such that substantial unrestricted rotation of the stem may be effected when the projection is between certain pairs of adjacent shoulders until said projection abuts against a shoulder, whereupon further movement is moderately restricted, and such that substantial unrestricted rotation of the stem may be effected when said arcuate portions are over the projection until said projection slides off said shoulders, whereupon said spring means forces said plates toward each other to provide audible indications.

3. In a valve according to claim 2 wherein the plate rotatable with said stem is rotatable a limited extent relative to the stem.

4. In a valve according to claim 2 wherein the plate rotatable with said stem is provided with a stop defining portion engageable with shoulders fixed relative to the body to determine the limits of movement of said stem.

5. A position indicating and determining mechanism for a valve comprising a body and operable by a rotatable stem extending outside the body, including in combination, a first plate fixedly secured relative to said body and apertured for the passage of the stem therethrough, a second plate located adjacent said plate rotatable by and to a limited extent relative to said stem, and spring means for urging said second plate toward said first plate, one of said plates having a pair of diametrically opposite projections of narrow arcuate extent facing toward the other plate, and the other plate having opposed diametrically opposite shoulders defined by arcuate recesses, said first plate being so located with respect to the stem and second plate, that in one position of the stem the projections of one plate abut against the other plate thereby forcing the movable plate away from the other against the spring means, and that when the stem is rotated in one direction from said one position to a second predetermined position the movable plate is rotated and the projections fall off said shoulders and the spring effects rapid movement of the movable plate toward the fixed plate to provide an audible indication, the stem being thereafter movable in the opposite direction to a third predetermined position determined by moderate restriction of movement thereof by engagement of said projections with said shoulders.

6. A position indicating and determining mechanism for a valve comprising a body and operable by a rotatable stem extending outside the body, including in combination, a first plate fixedly secured relative to said body and apertured for the passage of the stem therethrough, a second plate located adjacent said plate rotatable by and to a limited extent relative to said stem, and spring means for urging said second plate toward said first plate, one of said plates having a pair of diametrically opposite projections of narrow arcuate extent facing toward the other plate, and the other plate having two pairs of opposed diametrically opposite shoulders defined by opposed arcuate recesses, said shoulders being spaced apart distances substantially greater than the arcuate extent of said projections, said first plate being so located with respect to the stem and second plate that in one position of the stem the projections of one plate abut against the other plate thereby forcing the movable plate against the spring means, and that when the stem is rotated in one direction from said one position to a second predetermined position the movable plate is rotated and the projections fall off one pair of diametrically opposite shoulders and the spring effects rapid movement of the movable plate toward the fixed plate to provide an audible indication, the stem being thereafter movable in the same direction to a third predetermined position determined by moderate restriction of movement thereof by engagement of said projections with another pair of diametrically opposite shoulders.

7. A position indicating and determining mechanism for a valve comprising a body having spaced apart fixed shoulders and operable by a rotatable stem extending outside the body, including in combination, a first plate fixedly secured relative to said body and apertured for the

passage of the stem therethrough, a second plate located adjacent said plate rotatable by and to a limited extent relative to said stem, and spring means for urging said second plate toward said first plate, one of said plates having a pair of diametrically opposite projections of narrow arcuate extent facing toward the other plate, and the other plate having two pairs of opposed diametrically opposite shoulders defined by arcuate recesses, said shoulders being spaced apart distances substantially greater than the arcuate extent of said projections, said first plate being so located with respect to the stem and second plate, that in one position of the stem the projections of one plate abut against the other plate thereby forcing the movable plate against the spring means, and that when the stem is rotated in one direction from said one position to a second predetermined position the movable plate is rotated and the projections fall off one pair of diametrically opposite shoulders and the spring effects rapid movement of the movable plate toward the fixed plate to provide an audible indication, the stem being thereafter movable in the same direction to a third predetermined position determined by moderate restriction of movement thereof by engagement of said projections with another pair of diametrically opposite shoulders, and finally to a fourth predetermined position wherein the projections of said one plate abut against the other plate, said movable plate having a stop defining shoulder engageable with a fixed shoulder on the body for determining said fourth position.

8. A position indicating and determining mechanism for a valve comprising a body and operable by a rotatable stem extending outside the body, including in combination, a first plate fixedly secured relative to said body and apertured for the passage of the stem therethrough, a second plate located adjacent said plate rotatable by and to a limited extent relative to said stem, and spring means for urging said second plate toward said first plate, one of said plates having a pair of diametrically opposite projections of narrow arcuate extent facing toward the other plate, and the other plate having two pairs of opposed diametrically opposite shoulders defined by arcuate recesses, said shoulders being spaced apart distances substantially greater than the arcuate extent of said projections, said first plate being so located with respect to the stem and second plate, that in one position of the stem the projections of one plate abut against the other plate thereby displacing the movable plate against the spring means and, that when the stem is rotated in one direction from said one position to a second predetermined position the movable plate is rotated and the projections fall off one pair of diametrically opposite shoulders and the spring effects rapid movement of the movable plate toward the fixed plate to provide an audible indication, the stem being movable further in the same direction to a third predetermined position determined by moderate restriction of movement thereof by engagement of said projections with another pair of diametrically opposite shoulders, and thereafter to a position wherein the projections of said one plate abut against the other plate to displace said movable plate, said stem thereafter being movable in the opposite direction to a position wherein the projections fall off said other pair of shoulders and the spring again effects rapid movement of the movable

plate toward the fixed plate to provide an audible indication.

9. A position indicating and determining mechanism for a valve comprising a body having spaced apart fixed shoulders and operable by a rotatable stem extending outside the body, including in combination, a first plate fixedly secured relative to said body and apertured for the passage of the stem therethrough, a second plate located adjacent said plate rotatable by and to a limited extent relative to said stem, and spring means for urging said second plate toward said first plate, one of said plates having a pair of diametrically opposite projections of narrow arcuate extent facing toward the other plate, and the other plate having two pairs of opposed diametrically opposite shoulders defined by arcuate recesses, said shoulders being spaced apart distances substantially greater than the arcuate extent of said projections, said first plate being so located with respect to the stem and second plate, that in one position of the stem the projections of one plate abut against the other plate thereby displacing the movable plate against the spring means and that when the stem is rotated in one direction from said one position to a second predetermined position the movable plate is rotated and the projections fall off one pair of diametrically opposite shoulders and the spring effects rapid movement of the movable plate toward the fixed plate to provide an audible indication, that when the stem is rotated further in the same direction to a third predetermined position further movement is moderately restricted by engagement of said projections with another pair of diametrically opposite shoulders, that the stem is thereafter rotatable in the same direction with the projections of one plate abutting against and displacing the other plate to a fourth predetermined position, said movable plate being provided with a stop defining shoulder engageable with a fixed shoulder on the body for determining said fourth position, the stem thereafter being movable in the opposite direction to a fifth predetermined position determined by the falling of the projections from said other pair of shoulders whereupon the spring means again effects rapid movement of the movable plate toward the fixed plate to provide an audible indication, to a sixth predetermined position determined by moderate restriction to further movement resulting from engagement of said projections with said one pair of diametrically opposite shoulders, and finally to said one position as determined by engagement of said stop defining shoulder with another fixed shoulder on the body.

10. A position indicating and determining mechanism for a valve comprising a body and operable by a rotatable stem extending outside the body, including in combination, a first plate fixedly secured to said body and apertured for the passage of the stem therethrough, a second plate located between said plate and body and rotatable by and to a limited extent relative to said stem, and spring means for urging said second plate toward said first plate, said first plate having a pair of diametrically opposite projections of narrow arcuate extent facing toward the second plate, and the second plate having two pairs of opposed diametrically opposite shoulders defined by arcuate recesses, said shoulders being spaced apart distances substantially greater than the arcuate extent of said projections, said fixed plate being so located with respect to the stem and movable plate, that in one position of the

stem the projections of the fixed plate abut against the movable plate thereby displacing the latter against the spring means, and that when the stem is rotated in one direction from said one position to a second predetermined position the movable plate is rotated and its projections fall off one pair of diametrically opposite shoulders and the spring effects rapid movement of the plate toward the fixed plate to provide an audible indication, the stem being movable further in the same direction to a third predetermined position determined by moderate restriction of movement thereof by engagement of said projections with another pair of diametrically opposite shoulders, and thereafter to a position wherein the projections abut against the fixed plate, said stem thereafter being movable in the opposite direction to a position wherein the projections fall off said other pair of shoulders and the spring again effects rapid movement of the movable plate toward the fixed plate to provide an audible indication.

11. A position indicating and determining mechanism for a valve comprising a body having spaced apart fixed shoulders and operable by a rotatable stem extending outside the body, including in combination, a first plate fixedly secured to said body and apertured for the passage of the stem therethrough, a second plate located between said plate and body and rotatable by and to a limited extent relative to said stem, and spring means for urging said movable plate toward said fixed plate, said fixed plate having a pair of diametrically opposite projections of narrow arcuate extent facing toward the movable plate, and the movable plate having two pairs of opposed diametrically opposite shoulders defined by arcuate recesses, said shoulders being spaced apart distances substantially greater than the arcuate extent of said projections, said fixed plate being so located with respect to the stem and second plate, that in one position of the stem the projections of the fixed plate abut against the movable plate to displace the latter against the spring means and that when the stem is rotated in one direction from said one position to a second predetermined position the movable plate is rotated and the projections fall off one pair of diametrically opposite shoulders and the spring effects rapid movement of the movable plate toward the fixed plate to provide an audible indication, that when the stem is rotated further in the same direction to a third predetermined position further movement is moderately restricted by engagement of said projections with another pair of diametrically opposite shoulders, that the stem is thereafter rotatable in the same direction with the projections of said fixed plate abutting against the movable plate to a fourth predetermined position, said movable plate being provided with a stop defining shoulder engageable with a fixed shoulder on the body for determining said fourth position, the stem thereafter being movable in the opposite direction to a fifth predetermined position determined by the falling of the projections from said other pair of shoulders whereupon the spring means again effects rapid movement of the movable plate toward the fixed plate to provide an audible indication, to a sixth predetermined position determined by moderate restriction to further movement resulting from engagement of said projections with said one pair of diametrically opposite shoulders, and finally to said one position as determined by said

stop defining shoulder engaging a second fixed shoulder on the body.

12. A position indicating and determining mechanism for a valve comprising a body and operable by a rotatable stem extending outside the body, including in combination, a first plate fixedly secured to said body and apertured for the passage of the stem therethrough, a second plate located between said plate and body and rotatable by and to a limited extent relative to said stem, and spring means for urging said second plate toward said fixed plate, said movable plate having a pair of diametrically opposite projections of narrow arcuate extent facing toward the fixed plate, and the fixed plate having a pair of arcuate apertures defining two pairs of opposed diametrically opposite shoulders, said shoulders being spaced apart distances substantially greater than the arcuate extent of said projections, said fixed plate being so located with respect to the stem and movable plate, that in one position of the stem the projections of the movable plate abut against the fixed plate thereby displacing the latter against the spring means and, that when the stem is rotated in one direction from said one position to a second predetermined position the movable plate is rotated and the projections thereon fall off one pair of diametrically opposite shoulders and the spring effects rapid movement thereof toward the fixed plate to provide an audible indication, the stem being movable further in the same direction to a third predetermined position determined by moderate restriction of movement thereof by engagement of said projections with another pair of diametrically opposite shoulders, and thereafter to a position wherein the projections of said movable plate abut against the fixed plate to displace the former, said stem thereafter being movable in the opposite direction to a position wherein the projections fall off said other pair of shoulders and the spring again effects rapid movement of the movable plate toward the fixed plate to provide an audible indication.

13. A position indicating and determining mechanism for a valve comprising a body having spaced apart fixed shoulders and operable by a rotatable stem extending outside the body, including in combination, a first plate fixedly secured to said body and apertured for the passage of the stem therethrough, a second plate located between said plate and body and rotatable by and to a limited extent relative to said stem, and spring means for urging said movable plate toward said fixed plate, said movable plate having a pair of diametrically opposite projections of narrow arcuate extent facing toward the fixed plate, and the fixed plate having a pair of opposed arcuate apertures defining two pairs of opposed diametrically opposite shoulders, said shoulders being spaced apart distances substantially greater than the arcuate extent of said projections, said fixed plate being so located with respect to the stem and movable plate, that in one position of the stem the projections of the movable plate abut against the fixed plate thereby displacing the former against the spring means and that when the stem is rotated in one direction from said one position to a second predetermined position the movable plate is rotated and the projections thereon fall off one pair of diametrically opposite shoulders and the spring effects rapid movement thereof toward the fixed plate to provide an audible indication, that when the stem is rotated further in the same direction

to a third predetermined position further movement is moderately restricted by engagement of said projections with another pair of diametrically opposite shoulders, that the stem is thereafter rotatable in the same direction with the projections abutting against and displacing the movable plate to a fourth predetermined position, said movable plate being provided with a stop defining shoulder engaging a fixed shoulder on the body for determining said fourth position, the stem thereafter being movable in the opposite direction to a fifth predetermined position determined by the falling of the projections from said other pair of shoulders whereupon the spring means again effects rapid movement of the movable plate toward the fixed plate to provide an audible indication, to a sixth predetermined position determined by moderate restriction to further movement resulting from engagement of said projections with said one pair of diametrically opposite shoulders, and finally to said one position as determined by said stop defining shoulder engaging a second fixed shoulder on the body.

14. A position indicating and determining

mechanism for a valve comprising a body and operable by a rotatable stem extending outside the body, including in combination, a first plate fixed relative to the body and a second plate rotatable with and loosely connected relative to the stem, one of said plates having an arcuate recess therein of substantial arcuate extent defining a pair of spaced apart shoulders, the other of said plates having a projection adapted to slide off said shoulders when the stem is rotated in either direction, and spring means urging said movable plate toward the fixed plate, whereby an audible indication of the stem position is given as the stem is rotated in either direction to move said movable plate into positions wherein the projection falls into said recess.

15. A mechanism according to claim 14, wherein limited relative movement is provided between the plate movable by the stem and the stem, whereby two additional positions of the valve are indicated by restriction of movement of the stem when said projection strikes said shoulders.
